DESIGN FOR A JAR

Frasier Smith, Wheeling, W. Va., assignor to
Jewett & Sherman Co., Inc., Milwaukee, Wis.,
a corporation of Wisconsin

Application December 29, 1934, Serial No. 54,642

Term of patent 7 years

To all whom it may concern:

Be it known that I, Frasier Smith, a citizen of the United States, residing at Wheeling, in the county of Ohio and State of West Virginia, have invented a new, original, and ornamental Design for a Jar, of which the following is a specification, reference being had to the accompanying drawing, forming part thereof.

Figure 1 is a perspective view of a jar showing my new design; and

Figure 2 is an elevational view thereof.

I claim:

The ornamental design for a jar, as shown.

FRASIER SMITH.
